Attorney.

UNITED STATES PATENT OFFICE.

HENRY A. MAHOOD, OF PHILADELPHIA, PENNSYLVANIA, ASSIGNOR OF ONE-THIRD TO WILLIAM R. BRICE, OF SAME PLACE.

DESIGN FOR A GAME-BOARD.

SPECIFICATION forming part of Design No. 27,119, dated May 25, 1897.

Application filed March 16, 1897. Serial No. 627,890. Term of patent 14 years.

To all whom it may concern:

Be it known that I, HENRY A. MAHOOD, a citizen of the United States, residing in the city and county of Philadelphia, in the State of Pennsylvania, have invented certain new and useful Improvements in a Design for Game-Boards, of which the following is a full, clear, and exact description, reference being had to the accompanying drawings, of which—

- 10 Figure 1 is plan view. Fig. 2 is a section on line x x , Fig. 1.

My design for a game-board consists of a central circular space E and an outer space F and intermediate these spaces a series of 15 concentric lines, forming spaces or channels between adjacent lines, said lines and channels not being complete circles, but terminating, as shown, on each side of a radial line, together with a series of approximately radial lines and channels or passage-ways arranged with relation to the ends of the said concentric lines and channels, as shown, and hereinafter described. The end portions of 20 concentric channels below the radial line z z are marked, respectively, beginning with the one next to the space E, a' a^2 a^3 a^4 a^5 a^6 a^7 a^8 a^9 a^{10} a^{11} a^{12} a^{13} a^{14} a^{15} a^{16} a^{17} a^{18} a^{19} . The end portions of the said channels above the said 25 radial line are in like manner marked, consecutively, b' to b^{19} .

c , c' , c^2 , c^3 , c^4 , and c^5 are the series of approximately radial channels below the line z z ,

and d , d' , d^2 , d^3 , d^4 , and d^5 are the series of approximately radial channels above said line. The channel c communicates only between the space E and the circular channel ends a' and a^8 . c' communicates only with the several circular channel ends a^3 , a^4 , a^5 , a^6 , and a^7 ; c^2 , only with the circular channel ends a^9 and a^{17} ; c^3 , only with the ends a^{10} and a^{16} ; c^4 , only with the ends a^{18} and b' . The radial channel d communicates with the circular channel ends a^{19} and b^2 ; d' , only with the ends b^{19} and b^{12} and the outer space F; d^2 , only with the ends b^{17} , b^{16} , b^{15} , b^{14} , and b^{13} ; d^3 , only 45 with the ends b^{11} and b^3 ; d^4 , only with the ends b^4 and b^{10} , and d^5 with the ends b^9 , b^8 , b^7 , b^6 , and b^5 .

The essential features of my design are the series of concentric lines and channels or 50 passage-ways and the approximately radial lines and channels or passage-ways, together with the central and peripheral spaces, arranged as shown and described.

I claim—

The design for a game-board, substantially as herein shown and described.

In testimony whereof I have hereunto affixed my signature in the presence of two subscribing witnesses.

HENRY A. MAHOOD.

Witnesses:

WALTER C. PUSEY,
JOSHUA PUSEY.
